UNITED STATES PATENT OFFICE.

PETER E. JOHANSON, OF WARREN, PENNSYLVANIA.

ADJUSTABLE REAMER.

No. 895,090.

Specification of Letters Patent.

Patented Aug. 4, 1908.

Application filed August 27, 1907. Serial No. 390,279.

To all whom it may concern:

Be it known that I, PETER E. JOHANSON, a citizen of Sweden, (who has declared his intention to become a citizen of the United States,) residing at Warren, in the county of Warren and State of Pennsylvania, have invented new and useful Improvements in Adjustable Reamers, of which the following is a specification.

10 This invention relates to metal-working tools, such as reamers, taps, etc., designed especially to operate upon the wall or periphery of a cylindrical bore or perforation, either to enlarge the bore or aperture to a given dimension or to dress the same to a given contour, as in tapping the same for the insertion of a bolt; and the invention consists of the parts, and the constructions, arrangements and combinations of parts, forming the improved tool which I will hereinafter describe and claim.

In the accompanying drawings forming part of this specification and in which similar letters of reference indicate corresponding parts in the several views, Figure 1 is a part section and part elevation of an expansible reamer embodying my invention. Fig. 2 is a bottom plan view of the same. Fig. 3 is a detached view of the conical bolt. Fig. 4 is a plan view of the nut E. Fig. 5 is a side view of the washer F.

In carrying out my invention I construct the reamer with a lower or shell portion having an axial-opening or bore, a, said shell portion being split longitudinally through its sides from the lower or outer end to a point, B, as indicated in Fig. 1. The number of divisions of this shell-portion may be varied to suit the purposes for which the tool is used; 40 in the present instance I show said shell as divided radially into eight parts, each of which is externally grooved and longitudinally fluted on its outer surface and provided with cutting edges as is customary in this form of reamer. The shell is formed rigid or integral, with the upwardly extending shank, G, which has an internal bore or axial-opening of slightly smaller diameter than the opening, a, in the shell, said shell being adapted to be fitted into a suitable holder whereby the reamer may be operated.

At its outer end, the shell is formed with an enlarged cylindrical chamber, b, having parallel walls which extend inwardly to a point beyond the transverse plane of the outer end of the axial-opening or bore, a, said wall be-

ing substantially connected with the walls of the axial-opening, a, by means of inclined or tapering walls which constitute substantially a conical seat for the corresponding dished or recessed face of a washer, F, said washer having an exterior diameter substantially equal to that of the enlarged chamber mentioned and having sides which are parallel with the inner walls of said chamber.

Fitting the axial-opening or bore, a, is the bolt, D, which bolt is made tapering or cone-shaped and has its opposite ends threaded as shown in Figs. 1 and 3. One of these threaded ends is designed to screw into engagement with the reduced axial-opening or bore formed in the shank, G, and the other threaded portion is formed below a shoulder, c, on said bolt, and is adapted to receive the aforesaid collar and adjusting nut, as I will presently explain.

As shown in Fig. 1, the axial openings or bores, a and b, of the shell are substantially connected by means of an annular inclined wall which forms substantially a cone-shaped seat-portion at the base of the enlarged bore, b, said seat-portion being adapted for engagement with the beforementioned corresponding female-portion formed upon the surface of the annular washer, F, said washer having a central perforation to enable it to be slipped over the outer threaded end of the bolt, D, and to bear against the shoulder, c, formed at the base of said threaded portion.

Below the washer and adapted to engage the outer threaded end of the bolt, D, is the adjusting-nut, F, which bears against the washer and causes its dished or recessed portion to bear against the inclined walls of the sections of the reamer-shell to thereby hold said sections from spreading. The outer end of the shank extends beyond the outer threaded portion of said shank and the extremity of this extended portion is fashioned to receive a wrench or like tool whereby the shank may be turned to longitudinally adjust it relative to the shell of the reamer. As the adjusting-nut is also contained within the enlarged chamber, b, it is provided with notches or recesses adapted to be engaged by a spanner-wrench or like tool for screwing and unscrewing the nut and adjusting the same on the shank or bolt.

It will be observed in Fig. 1 that the shank or bolt has no portion projecting beyond the outer end of the reamer, shell and that the adjusting-nut and washer are contained

within the housing formed by the bore, *b*, and that they are within the plane of the outer end of said shell. By this construction the reamer may be used to enlarge or dress a cylindrical perforation or bored surface clear to the inner limits thereof and without any portion of the bolt or the nut coming in contact with an end wall of said perforation or bored surface.

10 Having thus fully described my invention, what I claim as new and desire to secure by Letters Patent, is:—

15 In a reamer, the combination with a shank portion and an integral shell portion fixed thereto and radially split from its outer end inward, said shell and shank having axially

aligned openings, and said shell having at its outer end an annular beveled seat with outwardly converging walls, a tapering bolt fitting the shell and screwing into said shank, a 20 washer having an annular recess in its surface with beveled or outwardly diverging walls engaging the beveled seat, and a nut threaded on said bolt and bearing against said washer.

25 In testimony whereof I have hereunto set my hand in presence of two subscribing witnesses.

PETER E. JOHANSON.
